UNITED STATES PATENT OFFICE.

EDGAR H. CRAIG, OF ROCKDALE, TENNESSEE.

AUTOMATIC WEIGHING-MACHINE.

1,386,319.

Specification of Letters Patent. Patented Aug. 2, 1921.

Application filed July 20, 1920. Serial No. 397,666.

To all whom it may concern:

Be it known that I, EDGAR H. CRAIG, a citizen of the United States, residing at Rockdale, in the county of Maury and State of Tennessee, have invented certain new and useful Improvements in Automatic Weighing-Machines; and I do hereby declare the following to be a full, clear, and exact description of the invention, such as will enable others skilled in the art to which it appertains to make and use the same.

This invention relates to an automatic weighing machine and has for its object to provide a mechanism which will be comparatively inexpensive to manufacture and more efficient in action than those which have been heretofore proposed.

With these and other objects in view the invention consists in the novel details of construction and combinations of parts more fully hereinafter disclosed and particularly pointed out in the claims.

Referring to the accompanying drawings forming a part of this specification in which like numerals designate like parts in all the views:

Figure 1 is a side elevational view partly broken away of a machine made in accordance with this invention;

Fig. 2 is a fragmentary sectional view taken on the line 2—2 of Fig. 1 looking in the direction of the arrows;

Fig. 3 is a sectional view through the bins and main body portion of the machine illustrating the construction of its interior; and

Fig. 4 is a sectional view taken through the larger diameter of the scale disk and associated parts of the machine looking toward the spout thereof.

1 and 1¹ indicate any suitable bins or containers for merchandise or other finely divided material such as coffee, sugar, rice, peas, etc.; 2 and 2¹, openings or windows therein covered with transparent material; and 3 a base piece on which said bins rest. Each of the bins are provided with an opening or delivery orifice 4 and 4¹ controlled by valve members 5 and 5¹ respectively sliding through openings in said base piece 3 and provided with the coil springs 6 and 6¹ to maintain said valve members in their closed positions. Said valve members 5 and 5¹ are provided with holes 7 and 7¹ adapted to register with their corresponding holes 4 and 4¹ when said members are pulled out against

the compressions of their springs 6 and 6¹. When said members are thus pulled out their notches 8 and 8¹ will be engaged by the upper ends 9 and 9¹ of the levers 10 and 10¹ pivoted at 11 and 11¹ respectively, and provided with toes 12 and 12¹, all as will be clear from Figs. 1 and 2 of the drawings. Said end 9 will thus hold the hole 7 of its valve 5 in registry with its corresponding hole 4 of the bin 1, until said end 9 is disengaged from its corresponding notch 8, whereupon the spring 6 will cause the said valve 5 to be drawn inwardly or into the position illustrated in Fig. 2 and thus to bring its hole 7 out of registry with its corresponding hole 4. The main body portion 13 of the machine is hollowed out to form the space 14, and is provided with the ears or lugs 15 having the perforations 16 through which bolts or other fastenings may be passed in order to secure the machine on any suitable wall or support. Said opening or space 14 has connected therewith the spout or delivery 17 which is tapered as shown and which may conveniently enter a bag or other container into which the merchandise is to be delivered. Closing the opening 14 is the disk like member 20 provided with the tubular member 21 on which it is loosely pivoted and through which passes the diamond shaped or knife edged member 22 as shown. Said member 22 conveniently screws or otherwise secures itself into the back portion 23 of the frame 13 and thus holds the disk 20 in place. The said frame 13 is cut away as at 24 to accommodate the disk 20 so that the outer surface 25 of said disk may lie flush with the outer surface 26 of said frame 13, while said disk may be freely rotated independently of the tubular member 21 of the knife edged member 22, all as will be readily understood from Figs. 1, 3, and 4. Also pivoted on the tubular member 21 and therefore rotating with the said disk 20 is the double cup device or weigher 27 provided with the receptacles 28 and 28¹ oppositely disposed as illustrated. Through said device 27, between the cups, passes the diamond shaped member 29 which screws into the disk 20 as illustrated and through the other end 30 of said device 27 passes the similar diamond shaped or knife edged member 31 which likewise screws in the said disk 20 as shown. When the disk is in one position one of the

cups 28 will register with the hole 4¹ and its cone shaped delivery spout 32 as shown, while after the disk 20 has made a revolution through 180°, the other cup 28¹ will 5 come into registry with the other hole 4 and its corresponding cone shaped delivery spout 33, all as will be clear from Fig. 3 of the drawings. On the outside of the said disk 20 there is located the scale beam 35 10 on which is adjustably secured the weight member 36 adapted to balance the weighing machine in a manner well known and also slidably mounted on said beam 35 is the adjustable beam weight or weighing member 15 37, as will be clear from Figs. 1 and 4.

It thus results that by suitably adjusting the weight 37 on the beam 35 said beam through its scale 38 will register "zero." This will be the condition when there is no 20 material in either of the cups 28 and 28¹. On the other hand, let us suppose that the valve 5¹ for example is pulled out until the end 9¹ of the lever 10¹ snaps into the notch 8¹ of said valve and thus holds the hole 7¹ 25 in registry with the hole 4¹. Material will now pass down through the hole 4¹, the cone shaped spout 32 and into one of the cups 28. In the meantime, the beam weight 37 has been adjusted along the scale 38 of the 30 beam 35 until it reaches the point which indicates the number of pounds it is desired to sell the customer. Material will therefore continue to flow through the delivery 32 until the beam 35 is tipped. When this 35 happens the roller 40 which is located in close proximity to the toe 12¹ of the lever 10¹ will strike said toe and will cause said lever 10¹ to swing on its pivot 11¹ and thus bring its end 9¹ out of the notch 8¹ where- 40 upon the spring 6¹ will pull inwardly the valve 5¹ and bring its hole 7¹ out of registry with the hole 4¹ and thus cut off the supply of material being furnished to the cup 28. The disk 20 may now be rotated by hand 45 on the tube 21 as an axis, until the filled cup turns upside down to deliver the weighed material down through the spout 17 into the bag or other receptacle, not shown, which is located under said spout. The re- 50 lation of the parts is such that the rotation of the disk and roller may continue until the other cup 28¹ is brought into registry with the other spout 33 ready for another operation through the pulling out of the 55 valve 5.

In the meantime the beam weight 37 being provided with a pointer 42, said pointer will have passed over the price scale 43 and will have indicated the particular figure 60 which corresponds to the cost of the number of pounds delivered to the said cup 28, all in a manner well known. Said beam weight 37 is provided with a duplicate pointer 42¹ which co-acts with the duplicate 65 scale 44 which last mentioned pointer and

scale will come uppermost when the other cup 28 registers with the delivery 33 and may thus be used for the next operation. When said next operation takes place the roller 45 carried by the disk 20 will have 70 passed beyond the toe 13 of the lever 10 and will be in the proper position above said toe to trip said lever and to cause the end 9 of said lever to disengage the notch 8 of the valve 5 when it is desired to cut 75 off material passing through the hole 4. Of course, in order to weigh material passing through said hole 4 it is only necessary to pull out the valve 5 in the manner described in connection with the valve 5¹, 80 whereupon the operation of the scale mechanism will proceed automatically as just disclosed. Said valves 5 and 5¹ may conveniently be provided with the ring members 48 to facilitate their operation, as will 85 be readily understood. It will now be clear that in order for the merchant to operate this machine it is only necessary for him to set the beam weight 37 at the proper point to indicate the number of pounds he 90 is to weigh, whereupon the pointers 42 or 43¹ will indicate on the scales 43 and 44 the cost of that particular number of pounds, whereupon he will pull out the valve 5¹ or 5, whereupon the ends 9¹ or 9 will hold the 95 corresponding valve open until the desired amount has flowed into one of the cups 28 or 28¹. When said amount has been thus delivered one of the rollers 40 or 45 will trip its corresponding lever, release its cor- 100 responding valve, shut off the material, and the said material will be dumped by hand through the delivery 17 into a receptacle not shown. In order that the disk 20 should be stopped after having turned through an 105 angle of 180°, said disk carries the pins 50 and 51 which take against the stationary member 52, which is sharp pointed as indicated and which therefore by registering with a line of the scale, shows when the 110 cups 28 or 28¹ are in the proper positions.

It is obvious that those skilled in the art may vary the details of construction as well as the arrangement of parts without departing from the spirit of the invention, and therefore it is not desired to be limited to the above disclosure except as may be required by the claims.

What is claimed is:—

1. In an automatic weighing machine the 120 combination of a receptacle to hold the material to be weighed; a pivoted receiver adapted to turn through an angle of substantially one hundred and eighty degrees located beneath said receptacle; a disk pro- 125 vided with a scale beam on which said receiver is mounted; a valve controlling the passage of material from said receptacle to said receiver; means moved by the turning of said receiver for controlling the flow of 130

material into said receiver; and a spout into which said receiver empties in its turning movements, substantially as described.

2. In an automatic weighing machine the combination of a receptacle to hold the material to be weighed; a pivoted receiver adapted to turn through an angle of substantially one hundred and eighty degrees located beneath said receptacle; a disk provided with a scale beam on which said receiver is mounted; a beam weight carried by said beam; a price scale carried by said disk with which said weight co-acts; a valve controlling the passage of material from said receptacle to said receiver; means moved by the turning of said receiver for controlling the flow of material into said receiver; and a spout into which said receiver empties in its turning movements, substantially as described.

3. In a weighing machine the combination of a pair of bins for holding the material to be weighed; an oscillating pivoted disk; a scale beam carried by said disk; a pair of oppositely disposed receivers carried by and oscillating with said disk adapted to alternately receive material from said bins; valves for controlling the passage of material from said bins to said receivers; and means controlled by the oscillations of said disk for controlling said valves, substantially as described.

4. In a weighing machine the combination of a pair of bins for holding the material to be weighed; an oscillating pivoted disk; a scale beam carried by said disk; a pair of oppositely disposed receivers carried by and oscillating with said disk adapted to alter-

nately receive material from said bins; spring pressed valves for controlling the passage of material from said bins to said receivers; and means comprising pivoted levers controlled by the oscillations of said disk for controlling said valves, substantially as described.

5. In a weighing machine the combination of a pair of bins for holding the material to be weighed; an oscillating pivoted disk; a scale beam carried by said disk; a pair of oppositely disposed receivers carried by and oscillating with said disk adapted to alternately receive material from said bins; valves for controlling the passage of material from said bins to said receivers; and means comprising rollers carried by said disk and pivoted levers controlled by the oscillations of said disk for controlling said valves, substantially as described.

6. In a weighing machine the combination of a pair of bins for holding the material to be weighed; an oscillating pivoted disk; a scale beam carried by said disk; a beam weight carried by said beam; a price scale carried by said disk with which said beam weight co-acts; a pair of oppositely disposed receivers carried by and oscillating with said disk adapted to alternately receive material from said bins; valves for controlling the passage of material from said bins to said receivers; and means comprising rollers and levers controlled by the oscillations of said disk for controlling said valves, substantially as described.

In testimony whereof I affix my signature.

EDGAR H. CRAIG.
